UNITED STATES PATENT OFFICE.

WILLIAM EVERETT VER PLANCK, OF ERIE, PENNSYLVANIA, ASSIGNOR TO GENERAL ELECTRIC COMPANY, A CORPORATION OF NEW YORK.

CONTROLLING MECHANISM FOR INTERNAL-COMBUSTION ENGINES.

1,094,406.

Specification of Letters Patent.

Patented Apr. 21, 1914.

Application filed April 18, 1912. Serial No. 691,643.

To all whom it may concern:

Be it known that I, WILLIAM E. VER PLANCK, a citizen of the United States, residing at Erie, county of Erie, State of Pennsylvania, have invented certain new and useful Improvements in Controlling Mechanisms for Internal-Combustion Engines, of which the following is a specification.

10 The present invention relates to the controlling of internal combustion engines and in particular to such engines where they are employed for driving self-propelled vehicles operating on the main and branch lines of existing steam railroads although the invention is not necessarily so limited. In such arrangements it is necessary to provide a means for initially starting the engine, as for example compressed air or other fluid.

15 It is also necessary to provide a throttle valve or equivalent means for controlling the admission of fuel to the engine.

20 My invention has for its object to so combine the starting means with the controlling or regulating means of the engine that it is impossible for the operator to increase the speed of the engine above a certain predetermined limit without shutting off the starting medium.

25 It is also an object of my invention to so combine the parts that once the starting regulator is released and permitted to close, it cannot be again picked up or moved by the actuator of the engine regulator without returning said actuator to its initial position.

30 In the accompanying drawing, which illustrates one of the embodiments of my invention, Figure 1 is a view in side elevation of the upper part of a controller; Fig. 2 is a plan view of the same, and Fig. 3 is a diagrammatic view, illustrating the relation of the parts.

35 1 indicates a base or support; in the present illustration it is the top of a controller for controlling the circuits of electric motors which receive current from a generator driven by the internal combustion engine. This controller is provided with an operating handle 2 and a handle 3 for reversing the connections of the motors. The handle 2 is arranged to move back and forth over a segmental plate 4 which is provided with notches to receive the latch 5. The lever 2 is rigidly mounted on a vertical tubular shaft

or sleeve 6. Located within the sleeve is a shaft 7 that is held in a bearing 8 carried by a bracket 9, which is bolted to the support 1. Mounted on the shaft 7 is an actuator or throttle lever 11. This lever is adapted to move between the stops 12 and 12^a. Stop 12 defines the initial position of the handle and stop 12^a defines the limit of the angular motion from left to right. The lever 11 is provided with a spring pressed latch having a hook 13, which engages a projection 14 on the sector 15, the latter being loosely mounted on the spindle 7. Pivotally attached to the sector is a link 16, whose outer end is connected to an arm 17, the latter being supported on a vertical pivot 18. On the lower end of the pivot is an arm 19 for actuating the regulator of the starting means.

20 65 70 75 80 85 90 95 100 105 110 indicates an adjustable stop to limit the inward movement of the arm 19 and hence the angular movement of the lever 11 so long as the parts 13 and 14 are in engagement. The object of this arrangement is to prevent the engineer from moving the throttle lever 11 over its entire range without first disconnecting the starting regulator by releasing the parts 13 and 14.

I prefer to use air starting means which is provided with a regulator comprising a casting 25 which contains a valve 26, the latter being mounted on a stem 27 that projects through a wall of the valve casing and engages the arm 19. The valve is also provided with a guiding and balancing piston 28. Between the piston and a fixed abutment is a coiled compression spring 29 which tends at all times to force the valve 26 against its seat at the same time causing the rod 27 to restore the parts 15 to 19 to their initial positions after the engaging parts 13 and 14 are released.

Referring to Fig. 3, 25 indicates the regulator for the air starting means, compressed air or other fluid under pressure being admitted between pipe 30 and discharged by the pipe 31 to the air distributing valves 32 and 33, the movable members of which are driven by the half speed cam shafts of the engine. Each valve comprises a suitable 105 110 casing and a rotary disk 34 that has a single port and as it is rotated permits air to enter the ports I, II, III and IV, which are connected by pipes 35 to the internal combustion engine cylinders 36, the latter being num-

bered to correspond to the ports in the distributing valve. In each one of these pipes is a check valve 37 which permits air to enter the cylinder but prevents the hot gases in the cylinder from being transmitted through the pipes to and beyond the distributing valves. The arrangement of the distributing valve 33 is the same and further description is therefore unnecessary. The arrangement of the distributing valves forms no part of the present invention except as they incidentally enter into the system.

Fuel to the engine cylinders is supplied by a manifold 38 to which fuel is admitted by the pipe 39 leading from a carburetor or other suitable source of supply. Located in this pipe is a regulator 40, which may be of any suitable construction adapted to control the passage of fuel from the source of supply to the engine.

The throttle valve shown is of the butterfly type, and is mounted on a spindle to which the arm 41 is connected. This arm is connected by suitable means, such as rods and levers, to the arm 42 which is rigidly mounted on the spindle 7 and moves at all times with the throttle lever 11. By moving the lever 11 back and forth between the two stops 12 and 12^a, the admission of fuel to the engine can be varied between the minimum and the maximum.

The operation of my invention is as follows: Assuming that it is desired to start the engine, the throttle lever 11 is moved up against the stop 12 and the hook 13 permits to engage the projection 14 on the sector 15. The lever 11 is then gradually moved toward the stop 12^a which causes the arm 19 to open the valve 26 and permit compressed air to pass from the supply pipe 30 to the distributing valves 32 and 33. Owing to the relation of the parts air will be admitted by one or the other of these distributing valves to an engine cylinder thus moving its piston outward from its head. This action turns the crank shaft and also rotates the distributing valves as in the normal operation of the engine. The result of this is to admit air to the engine cylinders in succession until the cylinders begin to fire in the ordinary way. This movement of the throttle lever 11 also opens the throttle valve 40 to a greater or less degree, depending upon the setting of the parts. As the throttle lever 11 is moved by the operator, the speed of the engine is gradually increased, assuming that the cylinders are firing, until the arm 19 engages the stop 20 when further movement of the lever can only be had by disconnecting the parts 13 and 14; in other words disconnecting the air starting regulator from the engine regulator. As soon as this happens the spring 29 forces the valve 26 against its seat and at the same time

swings the parts 15 to 19 back to their initial positions as shown in Fig. 2. Further movement of the lever 11 toward stop 12^a will increase the speed of the engine by admitting more fuel. The lever 11 can now be moved to and fro over its normal range without interfering with the air starting regulator.

It will be seen by reason of my improved construction that it is impossible for the operator to bring the engine up to full speed until he has released the air starting regulator; that the actuating means for said regulator is moved out of the normal working path of the throttle lever as soon as it is released, and that the operator can only reconnect the two regulators for simultaneous action by deliberately moving the throttle lever to its initial position against the stop 12.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is:

1. In combination, an internal combustion engine, a regulator therefor, a starting means for the engine, a regulator therefor, an actuator that is common to and moves both regulators, and means for disconnecting one of the regulators from the actuator.

2. In combination, an internal combustion engine, a regulator therefor, a starting means for the engine, a regulator therefor, an actuator for simultaneously moving both regulators during a portion of its stroke, means for limiting the simultaneous movements of the regulators, and means for disconnecting one of the regulators from the actuator and permitting the latter to complete its stroke.

3. In combination, an internal combustion engine, a regulator therefor, a fluid starting means for the engine, a regulating valve therefor, an actuator that is common to the regulator and valve, and means for disconnecting the valve and actuator and permitting the latter to move the regulator independently of the valve.

4. In combination, an internal combustion engine, a regulator therefor, a starting means for the engine, a regulator for said means which automatically returns to its initial position when released, an actuator that is common to both regulators, is permanently connected to one of them and is capable of moving it to and from its initial position, and means for disconnecting the starting means regulator from the actuator.

and permitting said actuator to actuate the engine regulator.

5. In combination, an internal combustion engine, a regulator therefor, a starting means for the engine, a regulator therefor, a lever for positively moving the engine regulator over its entire range of movement, a connecting means between the lever and the regulator of the starting means, and 10 means for disconnecting said connecting means from the lever.

6. In combination, an internal combustion engine, a regulator therefor, a fluid starting means for the engine, a regulating valve therefor, a lever for moving the engine regulator, an actuator for said valve, a means for automatically closing the valve when it is released, a connection between the valve actuator and lever, and means for releasing 20 said connection so that thereafter the lever can move the engine regulator independently of the regulating valve of the starting means.

7. In combination, an internal combustion engine, a regulator therefor, a fluid starting means for the engine, a regulating valve therefor, a lever for moving the engine regulator, an actuator for said valve, a releasable connection between the actuator and the 30 lever, one portion of which is carried by said lever, and an elastic means for automatically returning the regulating valve to

its initial position and moving a portion of the releasable connection out of the path of the lever when said connection is released.

8. In combination, an internal combustion engine, a regulator therefor, a fluid starting means for the engine, a regulating valve therefor, a lever for moving the engine regulator, a pivot therefor, a means mounted on 40 the pivot for actuating the regulating valve, and a controllable latch mounted on the lever for connecting and disconnecting the lever and said means.

9. In combination, an internal combustion engine, a regulator therefor, a starting means for the engine, a regulator therefor, means tending at all times to move the regulator of the starting means to its initial position, 45 an actuator that is common to both regulators, a stop to limit the range of movement of the actuator when both regulators are connected thereto, and means for connecting the actuator and the starting means regulator which can be caused to effect such connection only when both regulators are in 50 their initial positions.

In witness whereof, I have hereunto set my hand this sixteenth day of April, 1912.

WILLIAM EVERETT VER PLANCK.
